UNITED STATES PATENT OFFICE.

OSCAR H. NAVILLE, OF LA FAYETTE, INDIANA.

AUTOMATIC LOCOMOTIVE-CONTROLLING MECHANISM.

1,174,435.

Specification of Letters Patent.

Patented Mar. 7, 1916.

Application filed February 27, 1912. Serial No. 680,264.

To all whom it may concern:

Be it known that I, OSCAR H. NAVILLE, citizen of the United States, residing at La Fayette, in the county of Tippecanoe and 5 State of Indiana, have invented certain new and useful Improvements in Automatic Locomotive-Controlling Mechanisms, of which the following is a specification.

My invention relates to railroad applications, and particularly to means for automatically controlling the throttle valve and air brake mechanism of a railroad locomotive.

The primary object of my invention is the 15 provision of means whereby a locomotive and its train of attached cars may be automatically stopped without the intervention of the engineer at a certain specified point or points along the railway line, thus preventing the train from entering a block upon 20 which another train is standing, running by a stop signal either by accident or design, or crossing an intersecting track where there is danger of meeting another train thereon.

25 A further object is to provide a mechanism of the character described which will act to stop a train as above stated, and which is operable manually by a tower man or other employee.

30 A further object is to provide mechanism of this character which may be applied to any ordinary locomotive and which will necessitate very few changes in the construction of the locomotive cab and no 35 change in the locomotive equipment.

40 A further object is to provide in this connection a locomotive cab provided with current actuated valves controlling the passage of air to the air brake mechanism and the 45 passage of steam to the cylinders, said valves being so arranged that they may be operated upon the closing of a circuit but yet permit the manual actuation of the valves by the engineer whenever desired.

45 Further objects will appear in the course of the following description.

My invention is illustrated in the accompanying drawings wherein:

50 Figure 1 is a vertical transverse section through the upper portion of the cab of a locomotive showing my controlling mechanism in place therein. Fig. 2 is a partial vertical section; Fig. 3 is a detail perspective view of the armature carrying rod and the mounting for the same.

55 Corresponding and like parts are referred

to in the following description and indicated in all the views of the accompanying drawings by the same reference characters.

The locomotive designed to operate with 60 my improved controlling mechanism is provided on both sides with means for supplying current to wires designated 13^a extending into the cab and connected to a pair of electro-magnets designated 15 supported 65 on a bracket 16 or in any other suitable manner from the roof of the cab about the boiler 17. The return wire from the electro-magnet passes over to the other side of the cab as at 13^b and extends down to the current- 70 collecting members on that side. It will be understood of course that these wires 13^a and 13^b are protected by insulation.

Interposed in the length of the wires 13^a and 13^b is a signal lamp 18, which when the 75 current passes through the wires 13^a, 13^b is lighted so as to give a signal to the engineer. Mounted within the cab is the ordinary throttle lever 19 of any usual construction and connected to a throttle valve rod 20. 80 The throttle valve is also of any usual construction and therefore requires no special description.

For the purpose of actuating the throttle valve when the electro-magnets 15 are energized, I provide an armature 21 which is mounted upon a transversely extending guide rod 22 supported in any suitable manner but illustrated as slidably mounted in depending guides 23 extending from the 90 roof of the cab. The rod is formed on its outer extremity with a head 24, and disposed between this head and the guide 23 is a coil spring 25 which acts to retract the rod 22 and the armature and hold the armature 95 away from the electro-magnets when the latter are deenergized.

Extending from the boiler 17 is a steam pipe 26 which extends laterally and then downwardly and enters the forward end of 100 a cylinder 27 which for the purpose of this description is designated as the main cylinder, the position and construction of the main cylinder being illustrated in Figs. 1 and 2. In the length of this steam pipe is disposed a valve 28 which is connected by means of an arm 28^a to the rod 22 so that when the rod is moved toward the magnet 15, the valve 28 will be opened, permitting the passage of steam from the boiler to the 105 forward end of the main cylinder 27. When, however, the magnet is deenergized and the

spring 25 retracts the rod 22, the valve 28 will be closed, cutting off the supply of steam to the main cylinder 27.

Disposed within the main cylinder 27 is a piston 29 having a piston rod 30 which extends out through the end of the cylinder and is connected by a link 31 to the throttle lever 19. This throttle lever is connected by the link 32 to the throttle valve in a manner 10 evident to those skilled in the art. It will be seen then that when the valve 28 is opened the steam passes through the steam pipe 26 to the forward part of the main cylinder 27, forcing the piston 29 back to its full extent 15 and drawing the throttle lever forwardly, thus closing the throttle of the engine and cutting off the admission of steam to the cylinder.

Passing from a point intermediate the 20 ends of the main cylinder 27 is a conducting pipe 33 which enters the forward end of a cylinder 34 which for the purpose of this description is referred to as the air brake cylinder and which is provided near its rear 25 end with an exhaust pipe 35 leading to any suitable point of exhaust. Disposed within the air brake cylinder 34 is a piston 36, and mounted between the piston and the rear end of the air brake cylinder 34 is a spring 37 30 which acts to force the piston 36 outward.

Attached to the piston 36 and projecting through the front wall of the air brake cylinder, is a piston rod 38 which is connected to an arm 39 forming the actuating arm for 35 a valve 40 disposed in a by-pass 50. This by-pass 50 is mounted upon the air pipe 51 leading to the auxiliary reservoir and connects this air pipe with a train pipe 52 leading to the air brake system of the engine. 40 Ordinarily, passage of air to the air pipe from the train pipe is controlled by means of a handle 53, and when this handle is turned in one direction, it cuts off entirely 45 the supply of air to the pipe 51. When however the handle is turned in an opposite direction, the air brake system is set in operation. This by-pass 50 is intended to provide an automatic means for connecting the air pipe with the usual triple valve operating mechanism so that when the valve 40 50 is turned in one direction, the air brakes may be actuated while when turned in the other direction, the air brakes will remain unactuated.

55 As another signal to the engineer, when the throttle valve is turned to cut off communication between the boiler and the cylinders of the locomotive and when the air brake is thrown on, I provide a whistle 60 designated 54 and mounted upon a pipe 55 projecting from the pipe 26. As steam passes through this pipe 26 upon the opening of the valve 28, the steam will also pass through the whistle 54 and the whistle will 65 be actuated.

The operation of my invention is as follows. When the block is closed to the train, the signal-man sets the track apparatus so that immediately upon the entrance of the locomotive in the closed block, current will 70 be sent through the wires 13^a and 13^b and the electro-magnets energized. Immediately upon the energizing of the magnets 15, the armature 21 will be drawn toward the magnets and will throw open the valve 28. 75 Steam will then be admitted from the boiler to the main cylinder 27 and actuating the piston therein will draw over the throttle lever, thereby closing the throttle and cutting off communication with the engine cyl- 80 inders.

When the piston 29 is moved rearwardly beyond the end of the pipe 33 the steam will 85 pass down through said pipe and into air brake cylinder 34, shifting the piston 36 90 therein rearward against the action of the spring 37. This shifting over of the piston will open the valve 40 through the by-pass 50 and permit the brakes to be actuated. A further movement of the piston 36 rear- 95 ward to its full extent will permit the steam to pass out through the exhaust 35. Steam will continue to pass from the boiler through the cylinders 27 and 34 while the magnets 15 are energized. When the train backs out 95 of the block or the track apparatus is re- stored to normal after stoppage of the train, the magnets 15 will be deenergized. The spring 25 will then retract the armature, and in doing so will shift the valve 28 to 100 a closed position, thus cutting off the steam from the pipes 26 and 33. The engineer may then start up his engine by opening the throttle. This will cut off communica- 105 tion between the pipe 33 and the pipe 26 and reduce the pressure in front of the piston 36, and hence the spring 37 will force said piston outward, closing the valve 40 and releasing the brakes.

My invention is of particular value in 110 that it prevents an engineer running past a certain stopping point, either because he deliberately refuses to notice a stop signal, or because the stop signal is obscured, as in cases of fog, snow and the like. It will thus 115 be obvious that a tower or signal-man, for instance, may control the train by setting the track apparatus and that the train cannot go forward again until the block has been opened by the tower-man.

120 My invention is exceedingly simple, may be applied to locomotives at present in use with very small change therein, and does not require any elaborate change in the roadbed or addition thereto.

125 What I claim is:

1. A locomotive controlling mechanism including a pressure operated brake controlling valve, a valve controlling the supply of fluid pressure to said brake control- 130

ling valve, a throttle valve, means operable upon the opening of the fluid pressure controlling valve for closing the throttle valve and opening the brake controlling valve, a 5 swingingly mounted valve lever operatively connected to the pressure controlling valve, a reciprocally mounted rod terminating at one end in an armature and at the other end in a head provided with a slot through 10 which the end of the valve lever is slidable, the valve lever being normally inclined at an acute angle to the rod to facilitate its sliding in the slot of the rod, and an electro-magnet in a normally open or deenergized 15 circuit operatively disposed with respect to the armature terminal of the rod to cause reciprocation of the rod.

2. A locomotive controlling mechanism including a brake controlling valve, a valve controlling the supply of fluid pressure to the brake controlling valve, a throttle valve, means operable upon the opening of the fluid pressure controlling valve for closing the throttle valve and opening the brake 20

controlling valve, a swingingly mounted 25 valve lever operatively connected to the pressure controlling valve, a bracket, a rod reciprocally mounted in the bracket terminating at one end in an armature and at the other end in an enlarged head provided 30 with a slot through which the end of the valve lever is slidable, the valve lever being normally inclined at an acute angle to the plane of the rod to facilitate its sliding in the slot of the head, an electro-magnet in a 35 normally open or deenergized circuit operatively disposed with respect to the armature terminal of the rod to effect opening of the brake controlling valve, and a spring 40 held between the bracket and head for normally holding the rod in position to keep said valve closed.

In testimony whereof I affix my signature in presence of two witnesses.

OSCAR H. NAVILLE. [L. s.]
